RAILWAY SIGNALING SYSTEM

George W. Baughman, Pittsburgh, Pa., assignor to
 The Union Switch & Signal Company, Swiss-
 vale, Pa., a corporation of Pennsylvania

Application March 8, 1940, Serial No. 322,974

11 Claims. (Cl. 246—130)

My invention relates to railway traffic controlling apparatus of the type employing coded current in the track circuits thereof, and more particularly to the provision in a system of this character of improved track circuit detection means for the control of highway crossing signals or other apparatus.

Where a track section includes an intersection with a highway it is customary to divide the track section into subsections to facilitate control of the crossing signals which protect the intersection. On entrance of a train into the rearward or approach subsection operation of the crossing signals is initiated, while when the train vacates the rearward subsection it is desired to discontinue operation of the crossing signals without conditioning the signals governing movement of trains in the track section to display a proceed indication.

It has heretofore been proposed to provide in a system of this kind means operative when a train enters the forward or clearing subsection to supply to the track rails of the rearward subsection steady uncoded energy, and to provide means associated with the rearward subsection and operative on the supply of steady energy thereto to discontinue operation of the crossing signals.

If steady energy is supplied to a track circuit in which coded energy is normally employed, the advantage of improved shunting sensitivity which results from the use of coded current in the track circuit is lost as long as steady energy is supplied to the track circuit. Accordingly a following train entering the track section at a time when steady energy is supplied thereto might not effectively shunt the track relay for the section with the result that operation of the crossing signals would not be started and users of the highway would not be warned of the approach of the train.

It is an object of my invention to provide an improved railway signaling system of the type employing coded current in the track circuits thereof to control the signals governing movement of trains through the track stretch, the system also employing coded current in the track circuits for detection purposes to thereby provide the same degree of shunting sensitivity at such times as is normally obtained in the track circuits.

A further object of my invention is to provide, in a railway signaling system of the type employing coded current in the track circuits thereof to control the signals governing movement of trains through the track stretch, means to supply coded energy of a distinctive character to a track cir-

cuit to detect occupancy of the section without affecting the signals governing traffic in the track stretch.

Another object of my invention is to provide an improved railway signaling system having a track section having a track circuit including means responsive to coded current of one relative polarity for controlling the signals which govern movement of trains through the track section, and having means responsive to coded current of the other relative polarity for detecting occupancy of the track section to thereby enable coded current to be employed to detect occupancy of the track section without interfering with the means controlling the signals governing traffic in the track section.

A further object of my invention is to provide an improved signaling system of the type described and adapted for use in track stretches where coded alternating current is supplied to the track rails of the track sections to actuate vehicle carried signal apparatus, the system being arranged so that when coded direct current of the polarity employed for detection purposes is supplied to a track section coded alternating current will not be supplied thereto to thereby insure that at such times the vehicle carried signaling apparatus will be conditioned to provide its most restrictive indication.

Another object of my invention is to provide an improved railway signaling system.

I shall describe one form of apparatus embodying my invention, and shall then point out the novel features thereof in claims.

In the drawing the single figure is a diagram of a stretch of railway track equipped with coded signaling apparatus embodying my invention.

Referring to the drawing, there is shown therein a stretch of railway track having track rails 1 and 2 over which traffic normally moves in the direction indicated by the arrow, that is, from left to right. The rails of the track stretch are divided by insulated joints 3 into track sections for signaling purposes. One of these sections includes an intersection with a highway and the rails of this section have insulated joints 3 therein to divide the section into subsections to facilitate control of the interlocking relay XR which controls the crossing signals XS which protect the highway intersection. The two subsections are designated A1T and B1T, while portions of two track sections are shown and are designated 10T and 12T.

Each of the principal track sections has adjacent the entrance end thereof a wayside signal,

designated S with an appropriate prefix, for governing movement of trains in the track section. As shown the signals are of the familiar color light type, each having a green or clear lamp G, a yellow or caution lamp Y, and a red or stop lamp R. The invention, however, is not limited to a system employing this type of wayside signals, and any suitable signals may be employed. Furthermore, the invention is not limited to a signaling system employing wayside signals, but is equally applicable to a system which has cab signals only.

The rails of each of the track sections form a part of a track circuit to which direct current coded or periodically interrupted at either of a plurality of different frequencies is supplied at a point adjacent the exit end of the track section to control the wayside signals, while coded alternating current is also supplied to the track circuits to operate cab signaling apparatus carried by locomotives operating through the track stretch.

Each of the track sections has adjacent the entrance end thereof a code following track relay TR having a winding receiving energy from the rails of the associated track section. The track relays are of a type which are responsive to direct current of one relative polarity only, while current of opposite relative polarities is employed in the track circuits of adjoining track sections to prevent improper operation of the track relay of one of the sections in the event the insulated joints separating the rails of the sections become defective.

The subsection B!!T is provided with an auxiliary code following track relay B!!TRA having its winding connected in series with that of the principal track relay B!!TR. The relays B!!TR and B!!TRA are arranged so that one relay responds to current of one polarity only and so that the other responds to current of the other polarity only.

The track relays 12TR and B!!TR each have associated therewith decoding means selectively responsive to code following operation of the relay to control the associated signal, and to also control the supply of coded direct and alternating current to the rails of the adjoining track section in the rear. As shown the decoding means associated with each of these track relays comprises a decoding transformer DT, auxiliary relays H and J, a code transmitter CT, a track transformer TT, and a track battery TB.

The primary windings of the track transformers TT are supplied with alternating current from a suitable source, the terminals of which are designated BX and CX, while each of the track relays has associated therewith a source of direct current the terminals of which are designated B and C in the drawing.

The decoding means associated with the track relays 12TR and B!!TR is not a part of this invention and any suitable means of this type may be employed.

The track relays A!!TR and B!!TR each have associated therewith a front contact repeater relay FSA and a back contact repeater relay BSA. The track relay A!!TR also has associated therewith a track transformer B!!TT, a code transmitter A!!CT, and a track battery B!!TB.

As shown the code transmitters A!!CT and 12CT have continuously operated contacts 180 and 75 which provide track circuit current of two code frequencies, namely, current of 180 interruptions per minute over the periodically closed contact

180, and current of 75 interruptions per minute over the periodically closed contact 75.

The code transmitter A!!CT has one circuit making and breaking contact 29. While the coded direct current which is supplied to the rails of section B!!T for detection purposes may be of any desired frequency, it is preferred to employ a code frequency, such as 20 impulses per minute, which is substantially lower than the code frequencies employed in the control of the signals.

The equipment is shown in the condition which it assumes when the track stretch is vacant. At this time coded direct current of the 180 code frequency is supplied to the rails of section 12T by the means, not shown, associated with the adjacent section in advance. This energy is of the polarity which is effective to produce code following operation of the track relay 12TR.

As a result of movement of contact 22 of the track relay 12TR between its picked-up and released positions, the two end portions of the primary winding 21 of the decoding transformer 12DT are alternately energized with the result that energy is induced in the secondary windings 23 and 24 of the transformer. The contact 25 of the relay 12TR rectifies the current supplied from the secondary winding 23 of the transformer 12DT to the winding of the relay 12H and the contacts of the relay 12H are maintained picked up.

As the relay 12TR is responding to energy of the 180 code frequency, the frequency of the current induced in the secondary winding 24 is such that sufficient energy is supplied through the resonant rectifier unit 12RU to maintain the contact of the relay 12J picked up.

As contact 27 of relay 12H and contact 28 of relay 12J are picked up, the circuit of the green lamp G of signal 12S is established and this lamp is lighted. As contact 30 of relay 12H is picked up, the circuit of the 180 contact of the code transmitter 12CT is established and the circuit of the track battery 12TB and of the secondary winding 32 of the track transformer 12TT is intermittently established so as to supply coded alternating and direct current of the 180 code frequency to the rails of the clearing section A!!T.

The coded alternating current supplied to the rails of section A!!T serves to control vehicle carried signal apparatus on trains traversing the track section, while the coded direct current effects operation of the track relay A!!TR.

On the supply of coded direct current to the track relay A!!TR the contacts 35 and 36 are picked up and released. During the picked up periods of the contact 35 energy is supplied to the winding of relay A!!FSA, while during the released periods of contact 35 energy is supplied to the winding of relay A!!BSA over a circuit which includes front contact 38 of relay A!!FSA. A resistor 40 is connected across the terminals of the winding of relay A!!FSA to render the relay contacts slow to release, while contact 38 when picked up establishes a circuit to connect a resistor 41 across the terminals of the winding of the relay A!!BSA to render the contacts of this relay slow to release. Accordingly, as the track relay A!!TR is responding to coded energy, the relays A!!FSA and A!!BSA are both energized and their contacts are picked up, while the contacts of these relays are slow enough in releasing to remain picked up during the intervals between the supply of impulses of energy to the relay windings.

As the contacts 43 and 44 of the relays A!!BSA are picked up, a circuit is established to supply direct current energy of normal relative polarity from the track battery B!!TB to the rails of the approach section B!!T during the released periods of the track relay contact 36. This circuit is traced from track rail 2 of section B!!T through wire 45 and front contact 44 of relay A!!BSA to one terminal of the track battery B!!TB, and from the other terminal of the battery through front contact 43 of relay A!!BSA, back contact 36 of track relay A!!TR, and wire 46 to track rail 1 of section B!!T.

The circuit for supplying direct current to the rails of the approach section B!!T is interrupted during the picked-up periods of the track relay contact 36. Accordingly energy of the same code frequency is supplied to the rails of section B!!T as is supplied to the track relay A!!TR.

During the picked up periods of the track relay contact 36 a circuit is established for supplying energy from the secondary winding 32 of the track transformer B!!TT to the rails of section B!!T. This circuit is traced from rail 2 of section B!!T through wire 45 to one terminal of the transformer secondary winding 32, and from the other terminal of the winding 32 through front contact 36 of the track relay A!!TR and wire 46 to rail 1 of section B!!T.

The circuit for supplying alternating current to the rails of section B!!T is interrupted during the released periods of the track relay contact 36 with the result that the alternating current supplied to the rails of section B!!T is coded at the same code frequency as the direct current supplied to the track relay A!!TR.

From the foregoing it will be seen that when the track relay A!!TR is responding to coded energy, impulses of direct current are supplied to the rails of section B!!T during the released periods of the track relay contacts, and that during the picked-up periods of the track relay contacts impulses of alternating current are supplied to the rails of section B!!T.

In addition it will be seen that during the picked-up periods of the track relay contacts a shunt circuit is established between the track rails 1 and 2 of section B!!T through the secondary winding 32 of track transformer B!!TT. This circuit is of relatively low resistance and provides means to dissipate any charge built up between the track rails 1 and 2 by the supply of impulses of direct current thereto. As the track rails are shunted during the intervals between the supply of impulses of direct current energy thereto, the accumulation of a charge between the track rails which might interfere with operation of the track relays is prevented.

At this time as contact 43 of relay A!!BSA is picked up, the circuit of the winding 49 of interlocking relay XR is established and this winding is energized.

As the track stretch is assumed to be vacant, coded direct current supplied to the rails of section B!!T feeds to the track relays B!!TR and B!!TRA and flows through the windings of these relays in series. As stated above, the track relays B!!TR and B!!TRA are arranged so that they respond to current of opposite relative polarities. The relays B!!TR and B!!TRA are arranged so that only the relay B!!TR will respond to energy of the polarity which is supplied thereto when the contacts of the relay A!!BSA are picked up. Accordingly at this time the relay B!!TR responds to coded direct cur-

rent, while the contact of the relay B!!TRA remains in its released position.

As the contact 50 of relay B!!TRA remains in its released position at this time, energy is not supplied to the windings of the relays B!!FSA and B!!BSA and the contacts of these relays remain released.

As a result of code following operation of the track relay B!!TR, energy is supplied through the decoding transformer B!!DT to the relays B!!H and B!!J in the manner described in detail in connection with section 12T.

As the contacts of relays B!!H and B!!J are picked up, the circuit of the green or clear lamp G of signal 11S is established. In addition, as contact 30 of relay B!!H is picked up, the circuit for supplying coded alternating and direct current of the 180 code frequency to the rails of section 10T is established.

20 The relay B!!H has another contact 51 which when picked up establishes a circuit to supply energy to the winding 53 of interlocking relay XR. As both windings of the relay XR are energized, this relay maintains the crossing signals XS inactive.

Operation of equipment on passage of a train in normal direction of traffic

When a train moving in the normal direction of traffic enters the approach section B!!T, the track relay B!!TR is shunted and no longer responds to coded energy. At this time the cab signal equipment carried by the locomotive responds to the alternating current of 180 code frequency supplied by the equipment associated with relay A!!TR and provides the engineer with a clear signal.

As the relay B!!TR is shunted, energy is no longer supplied through the decoding transformer B!!DT to the relays B!!H and B!!J and the contacts of these relays become released.

As a result of release of contact 27 of relay B!!H, the circuit of the green lamp G of signal 11S is interrupted, and the circuit of the red or stop lamp R is established. As a result of release of contact 30 of relay B!!H, the circuit for supplying energy of the 180 code frequency to the rails of section 10T is interrupted and the circuit for supplying energy of the 75 code frequency is established.

55 In addition, as a result of the release of the contacts of relay B!!H, contact 51 interrupts the circuit for supplying energy to the winding 53 of interlocking relay XR. Accordingly, the armature controlled by this winding becomes released and effects operation of the crossing signals XS to warn users of the highway of the approach of a train.

When the train advances far enough in the track stretch to enter the clearing section A!!T, the track relay A!!TR is shunted and its contacts remain released. As contact 35 of relay A!!TR does not engage its front contact, energy is not supplied to the winding of relay A!!FSA. Accordingly, the contact 36 of this relay becomes released and interrupts the circuit of the winding of relay A!!BSA with the result that the contacts of relay A!!BSA become released.

70 As a result of the release of the contacts 43 and 44 of relay A!!BSA, the circuit traced above for supplying direct current energy of normal relative polarity to the rails of section B!!T during the released periods of the track relay contact 36 is interrupted, while a circuit

is established for supplying energy of the opposite or reverse relative polarity from the battery B11TB to the rails of section B11T. This circuit includes contact 20 of the code transmitter A11CT and is traced from rail 2 of section B11T through wire 45 and back contact 43 of relay A11BSA to one terminal of the battery B11TB, and from the other terminal of the battery through back contact 44 of relay A11BSA, front contact 20 of the code transmitter A11CT, back contact 55 of relay A11BSA, and wire 46 to rail 1 of section B11T. This circuit is interrupted during the released periods of contact 20 of the code transmitter A11CT, and the rate of operation of contact 20 is such as to close the circuit for supplying energy to the rails of section B11T twenty times a minute and to provide the same number of intervals of substantially equal duration during which energy is not supplied to the rails of section B11T.

During the released periods of contact 20 of the code transmitter A11CT a circuit is established which shunts the rails of the section B11T. This circuit is traced from track rail 1 of section B11T through wire 46, back contact 55 of relay A11BSA, back contact 20 of code transmitter A11CT, and wire 45 to rail 2 of section B11T. Since the rails of section B11T are shunted during the intervals between the supply of impulses of current thereto, the accumulation of a charge between the track rails at this time is prevented.

As a result of release of the contacts of relay A11BSA, contact 48 interrupts the circuit of winding 49 of interlocking relay XR. However, because of the internal construction of the relay XR, the armature controlled by winding 49 is prevented from moving all of the way to its released position since the armature controlled by winding 53 is already released.

As long as any portion of the train remains in the approach section B11T, the track relays B11TR and B11TRA continue to be shunted, but as soon as the rear of the train vacates section B11T, coded direct current supplied to the rails of the section feeds to the track relays B11TR and B11TRA.

The polarity of the direct current impulses supplied at this time is such that the track relay B11TRA will respond to these impulses, while the relay B11TR will not respond to these impulses and its contacts remain in their released positions.

As the contacts of the relay B11TR remain in their released positions, the signal 11S continues to display its stop indication, while energy of the 75 code frequency continues to be supplied to the rails of section 10T.

On movement of the contact 50 of relay B11TRA to its picked up position energy is supplied to the winding of relay B11FSA, and the contact of this relay becomes picked up so that on movement of contact 50 to its released position energy is supplied to the winding of the relay B11BSA. The relays B11FSA and B11BSA have snubbing resistors associated therewith to render the relay contacts slow in releasing, and these relays and the resistors are selected so that the relay contacts will remain picked up during the intervals between the supply of impulses of energy to the relay windings.

As a result of the supply of energy to the winding of relay B11BSA, contact 56 of the relay becomes picked up and establishes a circuit to supply energy to the winding 53 of the inter-

locking relay XR. The armature controlled by this winding accordingly becomes picked up and operation of the crossing signals XS is discontinued, while, because of the internal construction of the relay, the armature controlled by the winding 49 continues to be prevented from moving to its released position.

When the train advances far enough to enter the track section 12T, the track relay 12TR is shunted and energy is no longer supplied through the decoding transformer 12DT to the windings of the relays 12H and 12J. Accordingly the contacts of these relays become released and condition the signal 12S to display its red or stop indication, while the energy supplied to the rails of the clearing section A11T is changed from the 180 to the 75 code frequency.

As long as a portion of the train remains in section A11T, the track relay A11TR is shunted, 20 but when the rear of the train vacates the section, coded direct current of the 75 code frequency feeds to the winding of the track relay A11TR and produces code following operation of the track relay contacts, and as a result the contacts of the relays A11FSA and A11BSA become picked up.

On picking up of the contacts 43 and 44 of relay A11BSA, the circuit controlled by contact 20 of the code transmitter A11CT for supplying energy of reverse relative polarity to the rails of section B11T is interrupted, while the circuit is established for supplying energy of normal relative polarity to the rails of section B11T during the released periods of the track relay contact 36.

In addition, as a result of picking up of the contacts of the relay A11BSA, contact 55 interrupts the circuit controlled by code transmitter contact 20 for shunting the rails of the section B11T, while contact 48 of relay A11BSA establishes the circuit for supplying energy to the winding 49 of the interlocking relay XR. On the supply of energy to this winding the armature controlled by the winding is picked up and the relay is restored to its normal condition.

On movement of the track relay contact 36 to its picked-up position the circuit is established for supplying impulses of alternating current to the rails of section B11T and for shunting the track rails of the section, as explained above.

At this time as the track relay A11TR is responding to energy of the 75 code frequency, the energy supplied to the rails of section B11T is coded at this frequency.

On interruption of the supply of impulses of direct current of reverse relative polarity to the rails of section B11T the track relay B11TRA ceases to respond to coded energy, while on the supply of impulses of direct current of the normal relative polarity to the rails of section B11T the track relay B11TR responds to coded energy and energy is supplied through the decoding transformer B11DT to the winding of the relay B11H.

It will be seen that on each movement of the contacts of the track relay B11TR to their picked-up or released positions there is a change in energization of the decoding transformer primary winding, and that contact 25 of the relay establishes a circuit to supply an impulse of energy from the transformer secondary winding to the winding of relay B11H.

The relay B11H and the transformer B11DT are selected and proportioned so that the contacts of the relay when released will not become

picked up as a result of the supply of one impulse of energy from the transformer to the relay winding, or on the continued supply of impulses of energy at the frequency at which they are supplied when the track relay is responding to energy of a code frequency substantially lower than the 75 code frequency, such as, for example, energy of the 20 code frequency.

The relay B!!H and the transformer B!!DT are also selected and proportioned so that the relay contacts when released will become picked up on the supply in rapid succession of a plurality of impulses of energy from the decoding transformer, such as are supplied to the relay winding when the track relay is responding to energy of the 75 code frequency.

Since at this time the track relay B!!TR is responding to energy of the 75 code frequency, impulses of energy are supplied to the winding of relay B!!H which are effective to pick up the relay contacts after a plurality of such impulses of energy have been supplied to the relay winding. As the track relay B!!TR is responding to energy of relatively high code frequency, and since impulses of energy are supplied to the winding of the relay B!!H in both the picked-up and released positions of the track relay contacts, the plurality of impulses of energy necessary to pick up the contacts of the relay B!!H are supplied to the winding of the relay B!!H very quickly after initiation of code following operation of the track relay B!!TR.

It will be seen also that on initiation of code following operation of the track relay A!!TR the supply of energy of reverse relative polarity to the rails of section B!!T is continued until the contacts of relay A!!BSA become picked up, and that on picking up of the contacts of relay A!!BSA the supply of energy of normal relative polarity to the rails of section B!!T is initiated immediately. Accordingly, there is no time delay between cessation of code following operation of the track relay B!!TRA and initiation of code following operation of the relay B!!TR.

Because of the slow releasing characteristic of the relay B!!FSA a short time interval must elapse after the track relay B!!TRA ceases to follow code before the contacts of the relay B!!FSA become released, while the contacts of the relay B!!BSA release soon thereafter.

On release of the contact 56 of relay B!!BSA the circuit which it controls for supplying energy to the winding 53 of the interlocking relay XR is interrupted. However, as pointed out above, at this time the contacts of the relay B!!H become picked up promptly, and the various parts of the equipment are arranged so that the contact 51 of relay B!!H becomes picked up to establish the circuit which it controls before the contact 56 of relay B!!BSA becomes released. Accordingly on the change in the supply of energy to the rails of section B!!T from energy of reverse relative polarity to energy of normal relative polarity there is no interruption in the supply of energy to the winding 53 of the interlocking relay XR, and this relay, therefore, maintains the crossing signals XS inactive.

At this time as the track relay B!!TR is responding to coded energy of the 75 code frequency, the contacts of the relay B!!H are picked up, but insufficient energy is supplied through the resonant unit B!!RU to the winding of the relay B!!J to pick up the contacts of this relay. As the contact 28 of relay B!!J is released, and as the contacts of the relay B!!H are picked

up, the signal 11S is conditioned to display its yellow or caution indication, while contact 30 of relay B!!H interrupts the circuit for supplying energy of the 75 code frequency to the rails of section 10T and establishes the circuit for supplying energy of 180 code frequency thereto.

When the train vacates section 12T, energy of the 75 code frequency supplied to the rails of this section by the means associated with the track relay of the adjacent section in advance feeds to the relay 12TR and the equipment associated with this relay conditions the signal 12S to display its caution indication, while the energy supplied to the rails of section A!!T is changed from 75 to 180 code frequency.

On this change in the frequency of the energy supplied to the rails of section A!!T there is an increase in the rate of operation of the contacts of the track relay A!!TR, and a corresponding change in the frequency of the code supplied to the rails of section B!!T. Accordingly the contacts of relay B!!TR operate at a higher rate and sufficient energy is supplied through the resonant unit B!!RU to pick up the contact of relay B!!J with the result that signal 11S displays its clear indication instead of its caution indication.

From the foregoing, it will be seen that the system provided by this applicant normally employs coded direct current in the track circuits of the various track sections to control the signals governing movement of trains through the track stretch and to normally maintained the crossing signals inactive.

It will be seen also that on passage of a train through the track stretch, that when the train enters the clearing subsection in advance of the crossing, the supply of coded energy of normal relative polarity to the rails of the approach subsection in the rear of the crossing is cut off, while coded energy of reverse relative polarity is supplied to the rails of the rearward or approach subsection.

The track circuit apparatus associated with the rearward subsection and controlling the signals governing traffic in the track stretch will not respond to energy of this relative polarity, and, therefore, the wayside signal controlled by this apparatus continues to display its most restrictive indication.

However, the approach subsection in the rear of the intersection has means including an auxiliary track relay which is responsive to the supply of coded energy of reverse relative polarity, and is operative to discontinue operation of the highway crossing signals and to thereafter maintain the crossing signals inactive as long as coded energy of reverse relative polarity continues to be supplied to the auxiliary track relay.

If a second train enters the rearward or approach subsection at a time when coded current of reverse relative polarity is being supplied thereto, the auxiliary track relay will be shunted and the relays B!!FSA and B!!BSA controlled thereby will become deenergized and contact 56 of relay B!!BSA will interrupt the circuit for supplying energy to the winding 53 of the interlocking relay XR so that this relay will initiate operation of the crossing signals XS to warn users of the highway of the approach of the train.

It will be seen that at this time the shunting sensitivity of the track circuit of the rearward subsection is determined by the code following auxiliary track relay B!!TRA with the result

that the shunting sensitivity of the track circuit is the same when energy is supplied to the track circuit to discontinue operation of a crossing signal as it is when energy is supplied to the track circuit to control the signals governing traffic in the track stretch.

In addition it will be seen that when coded direct current of reverse relative polarity is supplied to the approach section that the supply of coded alternating current to the rails of the section is interrupted so that if a train enters the subsection the cab signal apparatus on the locomotive will display its most restrictive indication.

Furthermore, it will be seen that the frequency of the coded current supplied to the rails of the subsection in the rear of the crossing for the purpose of discontinuing operation of a crossing signal is much lower than the frequency of the code employed for the control of the traffic governing signals. If for any reason the track relay B11TR should respond to the energy of this low code frequency, insufficient energy would be supplied through the decoding transformer B11DT to the relay B11H to pick up the relay contacts and the signal 11S, therefore, would continue to display its stop indication. Similarly, if a train should enter the rearward subsection at a time when the forward subsection is occupied, the cab signal equipment on the locomotive would not respond to energy of this low code frequency to provide a proceed indication, even if for any reason coded alternating current were supplied to the rails of the track section.

Operation of equipment on movement of a train through the track stretch in the reverse direction

The system provided by this invention is arranged so that the crossing signals and the traffic governing signals will operate properly if a train travels through the track stretch in the reverse direction of traffic.

For purposes of illustration it will be assumed that the track stretch is vacant and that a train moving in the reverse direction, that is, from right to left travels through the track stretch.

As the stretch is assumed to be vacant, the track relays 12TR and B11TR are responding to energy of the 180 code frequency and the signals 12S and 11S are conditioned to display their green or clear indications.

When the train enters the adjacent section in advance of section 12T, the energy supplied to the rails of section 12T is changed from 180 to 75 code frequency with the result that signal 12S is conditioned to display its yellow or caution indication, while energy of 180 code frequency continues to be supplied to the rails of section A11T.

When the train enters section 12T, the track relay 12TR is shunted and the signal 12S is conditioned to display its red or stop indication, while the energy supplied to the section in the rear is changed from 180 to 75 code frequency. The track relay A11TR responds to the lower code frequency and repeats the supply of energy of the 75 code frequency to the rails of section B11T, while the signal 11S is conditioned to display its yellow or caution indication instead of its green or clear indication.

At this time as the track relays A11TR and B11TR are responding to coded energy, the circuits are established to supply energy to both of the windings of the interlocking relay XR and

this relay maintains the crossing signal XS inactive.

When the train advances into section A11T, the track relay of this section is shunted and its contacts thereafter remain in their released positions with the result that energy is not supplied to the winding of relay A11FSA and the contacts of this relay become released, thereby interrupting both the circuit of the winding of relay A11BSA and of the snubbing resistor 41 so that the contacts of the relay A11BSA become released.

On release of contact 48 of relay A11BSA the circuit of the winding 49 of the interlocking relay XR is interrupted, and the armature controlled by this winding becomes released and initiates operation of the crossing signals XS.

It will be seen that on shunting of the track relay A11TR the contacts of this relay move to their released positions, if they are not already in that position. On movement of the track relay contacts to their released positions the supply of energy to the winding of the relay A11FSA is cut off, while contact 36 establishes the circuit to supply energy to the rails of section B11T. This energy feeds to the track relay B11TR and picks up the contacts of the track relay with the result that there is a change in energization of the primary winding of the decoding transformer B11DT and an impulse of energy is supplied to the winding of the relay B11H. The operation of the equipment is such, therefore, that on shunting of the track relay A11TR an impulse of energy is supplied to the winding of the relay B11H subsequent to the interruption of energy to the winding of the relay A11FSA.

As a result of this supply of energy to the winding of the relay B11H, the contacts of the relay are maintained picked up, and contact 51 maintains the circuit for supplying energy to the winding 53 of the interlocking relay XR. The relay B11H is of a type the contacts of which are slow in releasing and this relay is selected so that its contacts will remain picked up until after the contacts of the relay A11BSA become released. The contacts of relay A11BSA release very soon after the contacts of the relay A11FSA release as the circuit of the snubbing resistor 41 is interrupted on release of the contacts of relay A11FSA, and release of the contacts of the relay B11H need not be delayed long after the release of the contacts of relay A11FSA to insure that the circuit of the winding 53 of the interlocking relay XR will not be interrupted until after the contact 48 of relay A11BSA becomes released to interrupt the circuit of the winding 49 of the interlocking relay XR.

Since the winding 49 of the relay XR is deenergized before the winding 53 is deenergized, the armature controlled by the winding 49 releases first and subsequent release of the armature controlled by the winding 53 will not interfere with the control of the crossing signals.

On release of the contacts of the relay A11BSA the circuit which includes a back contact of the track relay for supplying energy to the rails of section B11T is interrupted, and the circuit for supplying coded energy of reverse relative polarity to the rails of section B11T is established. Accordingly coded current of reverse relative polarity is supplied to the rails of section B11T and the auxiliary track relay B11TRA responds to this energy, while the contacts of the track relay B11TR remain released.

As the contacts of relay B11TR remain re-

leased, energy is no longer supplied through the decoding transformer B!!DT to the winding of the relay B!!H and the contacts of relay B!!H become released to condition the signal 11S to display its red or stop indication, and to change the energy supplied to the section in the rear from 180 to 75 code frequency. In addition, contact 51 interrupts the circuit of the winding 53 of the interlocking relay XR and the armature controlled by this winding moves toward its released position. However, as the armature controlled by the winding 49 is already in the released position, the armature controlled by winding 53 is prevented from moving all of the way to its released position.

As a result of code following operation of the auxiliary track relay B!!TRA, energy is supplied to the windings of the relays B!!FSA and B!!BSA and contact 56 of relay B!!BSA becomes picked up to establish a circuit to supply energy to the winding 53 of the interlocking relay XR. Accordingly the armature controlled by the winding 53 becomes picked up, while the armature controlled by winding 49 remains in its released position and maintains the crossing signals active.

From the foregoing it will be seen that when a train traveling in the reverse direction of traffic enters section A!!T, the supply of energy to the winding 49 of the interlocking relay XR is cut off and that this relay initiates operation of the crossing signals. In addition at this time the supply of energy of normal polarity to the section B!!TR is cut off so that energy is no longer supplied to the winding of the relay B!!H, but that the contacts of the relay B!!H remain picked up long enough to maintain the supply of energy to the winding 53 of the interlocking relay XR until after the winding 49 is deenergized so that operation of the crossing signals is controlled by the armature which is controlled by the winding 49.

When the train advances far enough in the track stretch to enter section B!!T, the relay B!!TRA is shunted and ceases to follow code with the result that the contacts of relays B!!FSA and B!!BSA become released. On release of contact 56 of relay B!!BSA the supply of energy to the winding 53 of the interlocking relay XR is interrupted. The armature controlled by this winding, therefore, moves towards its released position, but is prevented from moving all of the way to that position since the other armature of the relay is already in its released position.

When the rear of the train clears section 12T, the track relay of this section responds to coded energy of the 180 code frequency, and the signal 12S is conditioned to display its clear indication, while energy of the 180 code frequency is supplied to the rails of section A!!T.

When the rear of the train vacates section A!!T, coded energy feeds to the track relay A!!TR and produces code following operation of the relay so that the windings of relays A!!FSA and A!!BSA are energized. On picking up of the contacts of the relay A!!BSA the circuit for supplying coded energy of reverse relative polarity to the rails of section B!!T is interrupted, while the circuit for supplying coded current of normal relative polarity to section B!!T is established.

In addition, on picking up of the contacts of the relay A!!BSA contact 48 establishes the circuit to supply energy to the winding 49 of the interlocking relay XR. Accordingly the arma-

ture controlled by this winding becomes picked up and discontinues operation of the crossing signals XS, while because of the internal construction of the relay the armature controlled by the other winding of the relay is prevented from moving to its released position on picking up of the armature controlled by winding 49.

As long as any portion of the train remains in section B!!T, the track relays for the section 10 continue to be shunted, but when the rear of the train vacates the section, coded direct current of normal relative polarity feeds to the track relay B!!TR and produces code following operation of the relay. As a result, energy is supplied through the decoding transformer B!!DT to the windings of the relays B!!H and B!!J and the contacts of these relays become picked up to establish the circuit of the green or clear lamp of signal 11S.

In addition, on picking up of the contacts of the relay B!!H the energy supplied to the rails of section 10T is changed from 75 to 180 code frequency, while contact 51 establishes the circuit to supply energy to the winding 53 of the interlocking relay XR and the armature controlled by this winding becomes picked up.

The system provided by this invention employs polarized direct current in the track circuits, and the current employed in adjoining track circuits may be of opposite relative polarity to prevent improper operation of the signaling system in the event the insulated joints separating two sections are defective so that energy from one track section feeds across the defective joint to the rails of the adjoining section. With this arrangement energy feeding from the rails of one section across a defective joint to the rails of the adjoining section will be of the polarity opposite to that which is employed in the section to which the energy feeds, and since the code following track relays will respond to energy of one polarity only, they will not respond to energy supplied from the adjoining track circuits since it is of the wrong polarity.

Where the rails of a track section are normally supplied with coded energy of one relative polarity for the purpose of controlling the signals governing traffic in the stretch, and at other times are supplied with coded energy of the other relative polarity for detection purposes, as is the case in the approach section B!!T, it is necessary to provide means energized from the rails of the section and responsive to current of both polarities.

Accordingly, if energy from section 10T feeds across defective joints to the rails of section B!!T, the track circuit apparatus of section B!!T will respond to this current.

The equipment associated with section B!!T may be arranged so that either one of the two track relays will not respond to energy of the polarity supplied from the rails of section 10T, but the preferred arrangement is that in which the track relay B!!TR does not respond to this energy. If, therefore, the insulated joints separating the sections 10T and B!!T are defective so that coded energy from section 10T feeds to the rails of section B!!T, the track relay B!!TR will not respond to this energy and the signal 11S will not be improperly conditioned to display a proceed indication at times when section B!!T is occupied.

The energy which feeds over defective joints from section 10T to the rails of section B!!T

will effect operation of the track relay B!!TRA so that the windings of the relays B!!FSA and B!!BSA are energized and contact 56 of relay B!!BSA is picked up and establishes the circuit to supply energy to the winding 53 of the interlocking relay XR. This will result in failure of the crossing signals to operate at times, but it will not create a dangerous condition.

On passage of a train through the track stretch in the normal direction the track relays B!!TR and B!!TRA are shunted when the train enters section B!!T, and operation of the crossing signals XS is initiated as explained above. The energy from section 10T feeding across the defective joints is not effective to operate the track relay B!!TRA until the rear of the train is located some distance in advance of the entrance end of the section. Accordingly the crossing signals will be operated for a period prior to the time at which the train reaches the highway intersection, and users of the highway will have an indication of the approach of the train.

Since coded current of both relative polarities is supplied to the rails of section B!!T, if the joints separating the rails of this section from section A!!T become defective, energy of one or the other polarity supplied to the rails of section B!!T will effect operation of the track relay A!!TR.

In the preferred embodiment the equipment is arranged so that the track relay A!!TR will respond to energy of the polarity employed in the track section B!!T for detection purposes. When energy of this polarity is supplied to the rails of section B!!T, the section A!!T is occupied so that energy supplied at the exit end of section A!!T does not feed to the track relay A!!TR. If energy of reverse relative polarity feeds over defective joints to the relay A!!TR, the relay will respond to the coded energy until the contacts of relay A!!BSA become picked up. This interrupts the supply of energy to section B!!T until the contacts of relay A!!BSA become released, whereupon the cycle is repeated. As a result, energy of the 20 code frequency is intermittently supplied to the rails of section B!!T and there is no possibility that the signal 11S will be improperly conditioned to display a proceed indication.

From the foregoing it will be seen that this invention provides an improved railway signaling system in which coded direct current of one relative polarity is employed in a track circuit to control the traffic governing signals, while coded direct current of the other relative polarity is employed in the track circuit at times for detection purposes.

While the invention has been illustrated and described in connection with the control of a highway crossing signal, it should be understood that the invention is not limited to use in this connection and that it may be employed wherever it is desired to ascertain occupancy of a track section.

Although I have herein shown and described only one form of railway signaling system embodying my invention, it is understood that various changes and modifications may be made therein within the scope of the appended claims without departing from the spirit and scope of my invention.

Having thus described my invention, what I claim is:

1. In a coded railway signaling system, in combination, a stretch of railway track having a pair

of track rails divided by insulated joints into successive track sections, one of said sections including an intersection with a highway, the rails of said section having insulated joints therein in adjacent the intersection to divide the section into a forward and a rearward subsection, means governed by traffic conditions in advance of the section for selectively supplying to the rails of the forward subsection energy coded at either of a plurality of different frequencies, a code following electroresponsive device receiving energy from the rails of the forward subsection, means responsive to code following operation of said device for supplying to the rails of the rearward subsection direct current of one relative polarity coded at the same frequency as the energy supplied to said device, means controlled by said device and operative when said device is not responding to coded energy to supply to the rails of the rearward subsection coded direct current of the other relative polarity, a first and a second code following electroresponsive device receiving energy from the rails of the rearward subsection, the first device being responsive to direct current of said one relative polarity only and controlling means governing the supply of coded current to the rails of the adjacent section in the rear of the rearward subsection, the second device being responsive to the supply of direct current of the other relative polarity, a crossing signal protecting said highway intersection, means responsive to code following operation of said first device for maintaining said crossing signal inactive, and means responsive to code following operation of said second device for also maintaining said crossing signal inactive.

2. In a coded railway signaling system, in combination, a stretch of railway track having a pair of track rails divided by insulated joints into successive track sections, one of said sections including an intersection with a highway, the rails of said section having insulated joints therein in adjacent the intersection to divide the section into a forward and a rearward subsection, means governed by traffic conditions in advance of the section for selectively supplying to the rails of the forward subsection energy coded at either of a plurality of different frequencies, a code following electroresponsive device receiving energy from the rails of the forward subsection, means responsive to code following operation of said device for supplying to the rails of the rearward subsection direct current of one relative polarity coded at the same frequency as the energy supplied to said device, means controlled by said device and operative when said device is not responding to coded energy to supply to the rails of the rearward subsection coded direct current of the other relative polarity, a first and a second code following electroresponsive device receiving energy from the rails of the rearward subsection, the first device being responsive to direct current of said one relative polarity only and controlling means governing the supply of coded current to the rails of the adjacent section in the rear of the rearward subsection, the second device being responsive to the supply of direct current of the other relative polarity only, a crossing signal protecting said highway intersection, means responsive to code following operation of said first device for maintaining said crossing signal inactive, and means responsive to code following operation of said second device

second device for also maintaining said crossing signal inactive.

3. In a coded railway signaling system, in combination, a stretch of railway track having a pair of track rails divided by insulated joints into successive track sections, one of said sections including an intersection with a highway, the rails of said section having insulated joints therein adjacent the intersection to divide the section into a forward and a rearward subsection, means governed by traffic conditions in advance of the section for selectively supplying to the rails of the forward subsection energy coded at either of a plurality of different frequencies, a code following electroresponsive device receiving energy from the rails of the forward subsection, means responsive to code following operation of said device for supplying to the rails of the rearward subsection direct current of one relative polarity coded at the same frequency as the energy supplied to said device, means controlled by said device and operative when said device is not responding to coded energy to supply to the rails of the rearward subsection coded direct current of the other relative polarity, a crossing signal protecting said intersection, and means receiving energy from the rails of said rearward subsection, said means being operative when and only when responding to coded direct current of either relative polarity to maintain the crossing signal inactive, said means being operative when not responding to coded energy of said one relative polarity to establish a first supply circuit for supplying energy of one code frequency to the rails of the section in the rear of said rearward subsection and being operative when and only when responding to coded direct current of said one relative polarity to interrupt said first supply circuit and to establish a second supply circuit for supplying to the rails of the section in the rear of the rearward subsection energy of a second code frequency.

4. In a coded railway signaling system, in combination, a stretch of railway track having a pair of track rails divided by insulated joints into successive track sections, one of said sections including an intersection with a highway, the rails of said one section having insulated joints therein adjacent the intersection to divide the section into a forward and a rearward subsection, means governed by traffic conditions in advance of the section for selectively supplying to the rails of the forward subsection energy coded at either of a plurality of different code frequencies, a code following track relay for the forward subsection having a winding receiving energy from the rails of said forward subsection, a first supply circuit through which direct current of one relative polarity may be supplied to the rails of the rearward subsection, a second supply circuit through which alternating current may be supplied to the rails of the rearward subsection, said first and second supply circuits each including a contact of said track relay whereby when said track relay is responding to coded energy each of said supply circuits is interrupted at rates such that the energy supplied through said supply circuits is coded at the same frequency as the energy supplied to said track relay, a third supply circuit through which direct current of the other relative polarity may be supplied to the rails of the rearward subsection, means for periodically interrupting said third supply circuit, means responsive to and operative when and only when

said track relay is responding to coded energy to establish said first supply circuit and to interrupt said third supply circuit, said means being operative when said track relay is not responding to coded energy to interrupt said first supply circuit and to establish said third supply circuit, a crossing signal protecting said intersection, and means receiving energy from the rails of said rearward subsection, said means being operative when and only when supplied with coded direct current of either relative polarity to maintain said crossing signal inactive, said means being operative when not supplied with coded energy of said one relative polarity to establish a circuit to supply energy of a first code frequency to the rails of the adjacent section in the rear of said rearward subsection and being operative only on the supply of coded direct current of said one relative polarity to cut off the supply of energy of the first code frequency and to establish a circuit to supply coded energy of a second code frequency to the rails of the adjacent section in the rear of said rearward subsection.

5. In a coded railway signaling system, in combination, a stretch of railway track having a pair of track rails divided by insulated joints into successive track sections, one of said sections including an intersection with a highway, the rails of said one section having insulated joints therein adjacent the intersection to divide the section into a forward and a rearward subsection, means governed by traffic conditions in advance of the section for selectively supplying to the rails of the forward subsection energy coded at either of a plurality of different code frequencies, a code following track relay for the forward subsection having a winding receiving energy from the rails of said subsection, an auxiliary relay associated with said track relay, means responsive to code following operation of said track relay for supplying energy to the winding of said auxiliary relay, said auxiliary relay being operative when energized to establish a first supply circuit through which direct current of one relative polarity may be supplied to the rails of the rearward subsection and being operative when not energized to establish a second supply circuit through which direct current of the other relative polarity may be supplied to the rails of the rearward subsection, the first supply circuit including a contact of the track relay whereby energy supplied through said circuit is coded at the same frequency as the energy supplied to said track relay, means for intermittently interrupting the second supply circuit to code the current supplied through said circuit, a crossing signal protecting said intersection, means receiving energy from the rails of the rearward subsection and operative on the supply of coded direct current of either relative polarity to maintain said crossing signal inactive, said means being operative when not supplied with coded energy of said one relative polarity to establish a circuit to supply energy of a first code frequency to the rails of the adjacent section in the rear of said rearward subsection and being operative when and only when coded direct current of said one relative polarity is supplied thereto to cut off the supply of energy of the first code frequency and to establish a circuit to supply energy of a second code frequency to the rails of the adjacent section in the rear of said rearward subsection.

6. In a coded railway signaling system, in com-

bination, a stretch of railway track having a pair of track rails divided by insulated joints into successive track sections, one of said sections including an intersection with a highway, the rails of said one section having insulated joints therein adjacent the intersection to divide the section into a forward and a rearward subsection, means governed by traffic conditions in advance of the section for selectively supplying to the rails of the forward subsection energy coded at either of a plurality of different code frequencies, a code following track relay for the forward subsection having a winding receiving energy from the rails of said subsection, an auxiliary relay associated with said track relay, means responsive to code following operation of said track relay for supplying energy to the winding of said auxiliary relay, said auxiliary relay being operative when energized to establish a first supply circuit through which direct current of one relative polarity may be supplied to the rails of the rearward subsection and to also establish a first shunt circuit by means of which connection may be established between the rails of the rearward subsection, each of said circuits including a contact of the track relay and being arranged so that one circuit is established in one position of the track relay contact and the other circuit is established in the other position of the track relay contact, said auxiliary relay being operative when deenergized to establish a second supply circuit through which direct current of the other relative polarity may be supplied to the rails of the rearward subsection and to also establish a second shunt circuit by means of which connection may be established between the rails of the rearward subsection, means for alternately interrupting said second supply circuit and said second shunt circuit at a predetermined rate, said means being operative to interrupt each of said circuits before establishing the other of said circuits, a crossing signal protecting said intersection, and means receiving energy from the rails of the rearward subsection and operative on the supply of coded direct current of either relative polarity to maintain the crossing signal inactive, said means being operative when not supplied with coded direct current of said one relative polarity to establish a circuit to supply coded energy of a first code frequency to the rails of the adjacent section in the rear of said rearward subsection and being operative when and only when supplied with coded direct current of said one relative polarity to cut off the supply of energy of the first code frequency and to establish a circuit to supply energy of a second code frequency to the rails of the adjacent section in the rear of said rearward subsection.

7. In a coded railway signaling system, in combination, a stretch of railway track having a pair of track rails divided by insulated joints into successive track sections, one of said sections including an intersection with a highway, the rails of said one section having insulated joints therein adjacent the intersection to divide the section into a forward and a rearward subsection, means governed by traffic conditions in advance of the section for selectively supplying to the rails of the forward subsection energy coded at either of a plurality of different code frequencies, a code following track relay for the forward subsection having a winding receiving energy from the rails of said subsection, an auxiliary relay associated with said track relay, means responsive to code following operation of said track relay for supplying energy to the winding of said auxiliary relay, said auxiliary relay being operative when energized to establish a first supply circuit through which direct current of one relative polarity may be supplied to the rails of the rearward subsection and to also establish a first shunt circuit by means of which connection may be established between the rails of the rearward subsection, each of said circuits including a contact of the track relay and being arranged so that one circuit is established in one position of the track relay contact and the other circuit is established in the other position of the track relay contact, said auxiliary relay being operative when deenergized to establish a second supply circuit through which direct current of the other relative polarity may be supplied to the rails of the rearward subsection and to also establish a second shunt circuit by means of which connection may be established between the rails of the rearward subsection, means for alternately interrupting said second supply circuit and said second shunt circuit at a predetermined rate, said means being operative to interrupt each of said circuits before establishing the other of said circuits, a crossing signal protecting said intersection, and means receiving energy from the rails of the rearward subsection and operative on the supply of coded direct current of either relative polarity to maintain the crossing signal inactive, said means being operative when not supplied with coded direct current of said one relative polarity to establish a circuit to supply coded energy of a first code frequency to the rails of the adjacent section in the rear of said rearward subsection and being operative when and only when supplied with coded direct current of said one relative polarity to cut off the supply of energy of the first code frequency and to establish a circuit to supply energy of a second code frequency to the rails of the adjacent section in the rear of said rearward subsection.

relay associated with said track relay, means responsive to code following operation of said track relay for supplying energy to the winding of said auxiliary relay, said auxiliary relay being operative when and only when energized to establish a first supply circuit through which direct current of one relative polarity may be supplied to the rails of the rearward subsection and being operative when and only when deenergized to establish a second supply circuit through which direct current of the other relative polarity may be supplied to the rails of the rearward subsection, each of said supply circuits having associated therewith means for periodically interrupting said circuit to thereby supply coded energy to the rails of the rearward subsection through said supply circuit, a crossing signal protecting said intersection, and means receiving energy from the rails of the rearward subsection and operative on the supply of coded direct current of either relative polarity to maintain the crossing signal inactive, said means being operative when not supplied with coded direct current of said one relative polarity to establish a circuit to supply coded energy of a first code frequency to the rails of the adjacent section in the rear of said rearward subsection and being operative when and only when supplied with coded direct current of said one relative polarity to cut off the supply of energy of the first code frequency and to establish a circuit to supply energy of a second code frequency to the rails of the adjacent section in the rear of said rearward subsection.

8. In a coded railway signaling system, in combination, a stretch of railway track having a pair of track rails divided by insulated joints into successive track sections, one of said sections including an intersection with a highway, the rails of said one section having insulated joints therein adjacent the intersection to divide the section into a forward and a rearward subsection, means governed by traffic conditions in advance of the section for selectively supplying to the rails of the forward subsection energy coded at either of a plurality of different code frequencies, a code following track relay for the forward subsection having a winding receiving energy from the rails of said subsection, an auxiliary relay associated with said track relay, means responsive to code following operation of said track relay for supplying energy to the winding of said auxiliary relay, said auxiliary relay being operative when and only when energized to establish a first supply circuit through which direct current of one relative polarity may be supplied to the rails of the rearward subsection and to also establish a first shunt circuit by means of which connection may be established between the rails of the rearward subsection, each of said circuits including a contact of the track relay and being arranged so that one circuit is established in one position of the track relay contact and the other circuit is established in the other position of the track relay contact, said auxiliary relay being operative when deenergized to establish a second supply circuit through which direct current of the other relative polarity may be supplied to the rails of the rearward subsection and to also establish a second shunt circuit by means of which connection may be established between the rails of the rearward subsection, means for alternately interrupting said second supply circuit and said second shunt circuit at a predetermined rate, said means being operative to interrupt each of said circuits before establishing the other of said circuits, a crossing signal protecting said intersection, and means receiving energy from the rails of the rearward subsection and operative on the supply of coded direct current of either relative polarity to maintain the crossing signal inactive, said means being operative when not supplied with coded direct current of said one relative polarity to establish a circuit to supply coded energy of a first code frequency to the rails of the adjacent section in the rear of said rearward subsection and being operative when and only when supplied with coded direct current of said one relative polarity to cut off the supply of energy of the first code frequency and to establish a circuit to supply energy of a second code frequency to the rails of the adjacent section in the rear of said rearward subsection.

for maintaining said crossing signal inactive, and means responsive to code following operation of said first track relay for controlling the supply of coded energy to the rails of the adjoining section in the rear of said rearward subsection, said means being operative when said first track relay is not responding to coded energy to establish a circuit to supply energy of a first code frequency and being operative when said first track relay is responding to coded energy to establish a circuit supply energy of a second code frequency to the rails of said adjoining section in the rear of said rearward subsection.

9. In combination, a stretch of railway track intersected by a highway and comprising a signal approach section and a signal clearing section, a crossing signal for the intersection, means effective when said clearing section is unoccupied for supplying to the rails of the approach section train governing code comprising impulses of unidirectional current of one relative polarity, means responsive to entrance of a train into said clearing section for interrupting the supply of train governing code to the rails of said approach section and for supplying thereto detection code comprising impulses of unidirectional current of the other relative polarity, a first and a second electroresponsive device associated with said approach section, each of said devices having a winding receiving energy over the rails of the said approach section, the first device being responsive only to the supply of current of said one relative polarity and the second device being responsive to the supply of current of the other relative polarity, whereby said first device responds only to the train governing code and the second device responds to the detection code, and means responsive to code following operation of either of said devices for maintaining said crossing signal inactive, whereby said signal is inactive when the approach and clearing sections are unoccupied and is rendered active on entrance of a train into the approach section and is again rendered inactive when the train advances into the clearing section and vacates the approach section.

10. In combination, a stretch of railway track intersected by a highway and comprising a signal approach section and a signal clearing section, a crossing signal for the intersection, means effective when said clearing section is unoccupied to supply to the rails of the approach section train governing code comprising impulses of unidirectional current of one relative polarity, means responsive to entrance of a train into said clearing section for interrupting the supply of train governing code to the rails of said approach section and for supplying thereto detection code comprising impulses of unidirectional current of

the other relative polarity, and electroresponsive means receiving energy from the rails of said approach section and responsive to the supply of coded energy of either relative polarity to maintain the cross signal inactive, whereby said signal is inactive when the approach and clearing sections are unoccupied and is rendered active on entrance of a train into the approach section and is again rendered inactive when the train advances into the clearing section and vacates the approach section.

11. In a coded railway signaling system, in combination, a stretch of railway track having a pair of track rails divided by insulated joints into successive track sections including adjoining forward and rearward sections, the forward section including an intersection with a highway and being divided into an approach and a clearing subsection, a crossing signal for said intersection, means effective when the clearing subsection is unoccupied to supply to the rails of the approach subsection train governing code comprising impulses of unidirectional current of one relative polarity, means responsive to entrance of a train into said clearing subsection for interrupting the supply of train governing code to the rails of said approach subsection and for supplying thereto detection code comprising impulses of unidirectional current of the other relative polarity, and electroresponsive means receiving energy from the rails of said approach section, said means being operative on the supply thereto of either train governing or detection code to maintain the crossing signal inactive, said means also being operative when not supplied with train governing code to effect the supply of train governing code of a first character to the rails of said rearward section and being operative when supplied with train governing code to effect the supply of train governing code of a second character to the rails of said rearward section, whereby said crossing signal is inactive and train governing code of the second character is supplied to the rails of said rearward section when said approach and clearing subsections are unoccupied, and on entrance of a train into the approach subsection the signal is rendered active and train governing code of the first character is supplied to the rails of said rearward section, and whereby the signal is again rendered inactive when the train advances into the clearing subsection and vacates the approach subsection while train governing code of the first character is supplied to the rails of the rearward section until the train vacates the clearing subsection and thereafter train governing code of the second character is supplied to the rails of said rearward section.

GEORGE W. BAUGHMAN.
